UNITED STATES PATENT OFFICE.

WALTER GLASS, OF NEW YORK, N. Y., ASSIGNOR TO SIGMUND BERGMANN AND EDWARD H. JOHNSON, BOTH OF SAME PLACE.

ELECTRIC CIGAR-LIGHTER.

SPECIFICATION forming part of Letters Patent No. 307,759, dated November 11, 1884.

Application filed August 13, 1883. (No model.)

To all whom it may concern:

Be it known that I, WALTER GLASS, of New York, in the county of New York and State of New York, have invented a certain new 5 and useful Improvement in Electric Cigar-Lighters, of which the following is a specification.

The object of this improvement is to produce an electric cigar-lighter which will be 10 simple, easily operated, and withal durable.

In the accompanying drawings, Figure 1 is a diagrammatic view of an electric cigar-lighter embodying my improvement. Fig. 2 is a diagrammatic view of another electric cigar-lighter embodying the improvement, but modified in form. Fig. 3 is a sectional side view of the body of a torch for an electric cigar-lighter. Fig. 4 is a perspective view of a detachable plug forming part of the torch. Fig. 5 is an end view of this plug. Fig. 6 is a sectional view of the end of this plug. Fig. 7 is a sectional side view of the body of a torch of modified form. Fig. 8 is a perspective view of a removable plug forming part 25 of this torch. Fig. 9 is an end view of this plug. Fig. 10 is a sectional view of the end of this plug. Fig. 11 is a plan of a torch of modified form, and Fig. 12 is a transverse section of this torch.

30 Similar letters of reference designate corresponding parts in all the figures.

A designates the torch of the cigar-lighter.

I will first describe the torch shown in detail in Figs. 3, 4, 5, and 6.

35 The outer shell, *o*, of the body may be made of metal or other material and of any desirable contour. In the rear or bottom portion is arranged a disk, *A'*, of insulating material. At the extreme rear the shell is provided with 40 a socket, *a*, whereby it may be secured to any support.

B is a screw-threaded metal cylinder, which may be formed by spinning it out of sheet metal. It is mounted upon the disk *A'*, and 45 has openings *b* in opposite sides. Inside this cylinder, and between its openings *b*, a frame, *B'*, is arranged. This frame conforms to the interior of the cylinder B. The rear end or bottom of the cylinder is turned inward, and 50 the frame *B'* rests against it. Screws *c* are

passed through the disk *A'* and inserted in the frame *B'*, thereby securing the frame to the disk and clamping the rear end or bottom of the cylinder between the frame and disk. The frame *B'* is provided opposite one of the 55 openings *b* of the cylinder B with a binding-screw, *S*.

C is a diaphragm of insulating material that is fitted into the cylinder B just in front of the frame *B'*. On this diaphragm is secured by a 60 screw, *d*, a metal plate, *D*, that is bent over the diaphragm, and provided opposite one of the openings *b* of the cylinder B with a binding-screw, *S'*. Wires *E E'*, whereby an electric current is conducted to the torch, pass 65 through a hole or holes in the disk *A'*, and are fastened to the binding-screws *S S'*. The plug of this torch may be made of slate, plaster-of-paris, wood, or other insulating material. It has at the inner end a metal plate, *F*, and on 70 its exterior a cylindric screw-threaded metal shell, *G*. When the plug is screwed into the cylinder B, the cylindric screw-threaded metal shell *G* of the plug makes electrical contact with the said cylinder B, and the metal plate 75 *F* of the plug makes electrical contact with the metal plate *D*. Wires *H H'* lead, respectively, from the metal plate *F* and cylindric screw-threaded metal shell *G* of the plug to the outer end 80 of the plug. In the outer end 80 of the plug is a recess, *f*, in which is fitted a piece or disk of asbestos. A fine metal wire, *I*, is run or stitched back and forth through the asbestos and connected at the ends to the ends of the wires *H H'*. The asbestos forms 85 a support or backing for the wire *I*, thereby lessening the liability of the breakage of this wire. When a current of electricity passes through this wire, the wire becomes incandescent, or heated to such a degree as to be 90 capable of igniting a cigar pressed against it.

The torch shown in Figs. 7, 8, 9, and 10 is very similar to the one just described. On the diaphragm C, however, two spring-metal contact-pieces, *J J'*, are mounted. They are 95 secured by screws, and have the ends of the wires *E E'* clamped between them and the diaphragm. The plug in this case may be made of any suitable insulating material. It is provided with spring-metal contact-pieces *K K'*, 100

which may be inserted between the spring-metal contact-pieces J J', so as to make electrical contact therewith. The incandescent wire I is in this example of my improvement 5 connected to the plug at numerous points in its length by wires g, extending from the outer end of the plug.

In Figs. 11 and 12 I have shown a body, L, made of any suitable conducting material, 10 and consisting, essentially, of converging side plates, h. The wires E E' are fastened to it in such a way as to be insulated from each other. The plug is made of insulating material and like the body L in shape, although 15 made slightly narrower. It has an incandescent wire stitched or run through it, and the ends of this wire are in electrical communication with the wires E E' when the plug is in place in the body-piece.

20 Turning now to Figs. 1 and 2, it will be seen that the wires E E' are comprised in a cable, or, in other words, enveloped by a covering common to both. Of course, they are insulated from each other. This cable in the 25 examples of my improvement shown in Figs. 1 and 2 forms the sole support of the torches.

In each of the examples of the improvement shown in Figs. 1 and 2 the torch is shown as provided with a handle, M, extending from 30 the outer shell, o, of the body.

In Fig. 1 the wire E extends to a wire, N, forming one of the line-wires of a multiple-arc circuit, and the wire E' leads to a metal switch, P. When the torch hangs on the cable enclosing 35 the wires E E', it pulls down the switch P, so that it will not make contact with its contact-piece P'. From the contact-piece P' a wire, P², extends to incandescent electric lamps Q, and these lamps are connected to 40 the line-wire N' of the multiple-arc circuit. When the torch is lifted by its handle so that the switch P makes contact with its contact-point P', an electric current will traverse the incandescent wire I of the torch and heat it 45 sufficiently to adapt it for use in lighting a cigar. The electric lamps constitute a resistance to prevent injury to the incandescent wire of the torch. When the torch hangs from the cable comprising the wires E E', no 50 current traverses its incandescent wire.

In Fig. 2 the wire E leads to one pole of a battery, R, and the wire P², leading from the contact-piece P' of the switch P, connects with the other pole of the battery R.

55 The operation of the torch here shown is

like the operation of the torch shown in Fig. 1.

In all examples of my improvement the plug of the torch may be removed, if desirable, to facilitate repairing it or to replace it with another.

50

I am aware that it is not new to suspend a telephone from a switch by means of a non-conducting cord in such manner that the circuit will be broken when the telephone is supported by the cord, and I do not here claim 65 such a combination of parts.

I am also aware that it is old in electric cigar-lighters to operate the switch mechanism independently of any movement of the conducting-wires.

70

I am also aware that an incandescent lamp has been detachably secured in a socket and so combined therewith that a current might be transmitted from the socket to it.

What I claim as my invention, and desire 75 to secure by Letters Patent, is—

1. The combination of an electric torch, conducting-wires suspending the same, and a yielding switch to which one of the conducting-wires is connected, substantially as specified, whereby when the torch is suspended by the conducting-wires the switch will be opened through the weight of the torch, and when the torch is lifted for use the switch will be closed.

80

2. The combination, in an electric torch, of a body-piece connected to wires or conductors, a removable plug having an incandescent substance so arranged that when an electric current is passed through it it may be utilized 90 for lighting a cigar, and a support or backing for said incandescent substance, substantially as specified.

85

3. The combination, in an electric torch, of a body-piece connected to wires or conductors, a removable plug having an incandescent wire so arranged that it may be utilized for lighting a cigar when an electric current is passed through it, and a support or backing for said incandescent wire, substantially as specified.

95

4. The combination, in an electric torch, of a body-piece connected to wires or conductors, and a removable plug having an incandescent wire stitched or run through asbestos, substantially as specified.
